UNITED STATES PATENT OFFICE.

EDOUARD SCHLAEPFER, OF LAUSANNE, SWITZERLAND.

SPRAY NOZZLE.

Application filed April 11, 1927, Serial No. 182,851, and in Switzerland March 16, 1926.

The present invention relates to spray nozzles of the adjustable type in which the nozzle proper can turn on the threaded end of the outlet-pipe of any spraying apparatus, in order to set or adjust the spray, and in which this threaded end is an independent piece which may be screwed on the outlet-pipe of said apparatus.

Its object is to provide a nozzle of this type, which is easy to manufacture and in which an efficient tightness of the nozzle's joining on the pipe is very simply obtained. Besides, the end of the pipe in this nozzle terminates in the shape of the whirler member, and the oblique or spiral passages, recessed into the periphery of this whirler member, are widened at their outlet in order to obtain intermediate degrees of fineness of the spray between the mist and the full spray.

In the accompanying drawings Figs. 1 and 2 are axial sections of an embodiment of the invention in two different setting positions, and Fig. 3 a plan view of the whirler member.

This embodiment consists of 3 parts: *a*, *b*, *c*. One end of part *a* is threaded at *a*¹ in order to be screwed on the outlet-pipe of any kind of spraying apparatus. Besides, this part *a* is provided with a threaded part *a*² and terminates at its other end with a full cylindrical part *a*³ which forms the whirler member. Between this whirler member *a*³ and the threaded part *a*² is formed an annular groove *a*⁴. *a*⁵ shows the axial bore fitted for the passage of the liquid through part *a*. *a*⁶ indicates two radial passages which give communication between the bore *a*⁵ and the groove *a*⁴. Into the periphery of the whirler member *a*³ are drilled the usual oblique or spiral passages *a*⁷ which cause the whirling of the liquid necessary for atomizing the spray.

According to the invention, the section of these passages *a*⁷ is enlarged, as shown by *a*⁸ (see Fig. 3), on the side facing the outlet, in order to obtain intermediate degrees of fineness of the spray between the mist (Fig. 1) and full spray (Fig. 2).

The nozzle proper consists of two parts, *b*, *c*, screwed together, between which is enclosed a tightening leather-ring *d*. The

stuffing-box *c* may be screwed more or less deeply on the threaded portion *a*² of part *a*, in order to adjust the spray.

When the nozzle is set for the mist spray (Fig. 1), the liquid, arriving in the annular groove *a*⁴ through both passages *a*⁶ and the axial bore *a*⁵, cannot escape but through the little passages *a*⁷. To the contrary, when the nozzle is set for the full spray (Fig. 2), the liquid is allowed to escape from the groove *a*⁴ all around the whirler member *a*³. This is made possible by the fact that the bore of the nozzle proper *b* has a cylindrical hollow part *b*¹ from same diameter as the whirler member *a*³.

This embodiment may undergo several variations without the principle of this invention being affected. For instance, the nozzle proper *b*, *c* might consist of one single piece. In this case, the tightening-leather-ring *d* would be enclosed within an inner groove of that piece.

Finally, there may be more than two passages *a*⁶ or *a*⁷.

I claim:

A spray nozzle comprising two complementary members arranged for axial adjustment one upon the other, the inner member having a cylindrical terminal portion provided with peripheral inclined passages widening in section toward their discharge end, the outer member having a cylindrical seat into which said terminal portion fits as said members approach their limit of relative movement in one direction, said inner member being of reduced diameter below said terminal portion forming with said outer member an annular recess, said inner member being provided with a longitudinal bore and a transverse bore communicating therewith and with said recess, said outer member being formed with a conical walled chamber in advance of the cylindrical terminal portion of said inner member communicating with the inclined passages therein, and being placed in communication with said annular recess when said cylindrical terminal portion is withdrawn from its seat in the outer member.

In testimony whereof I have signed my name to this specification.

EDOUARD SCHLAEPFER.
